UNITED STATES PATENT OFFICE.

ALBERT J. TOBIE, OF WESTBURY, NEW YORK.

MECHANIC'S TOOL.

1,113,261.

Specification of Letters Patent.

Patented Oct. 13, 1914.

Application filed February 25, 1913. Serial No. 750,467.

To all whom it may concern:

Be it known that I, ALBERT J. TOBIE, a citizen of the United States, and residing at Westbury, in the county of Nassau and State of New York, have invented certain new and useful Improvements in Mechanics' Tools, of which the following is a specification, such as will enable those skilled in the art to which it appertains to make and use the same.

This invention relates to tools and particularly to mechanics' or carpenters' tools, and the object thereof is to provide an improved combination device of this class which may be used as an ordinary rule and also as a square and miter-square.

The invention is fully disclosed in the following specification of which the accompanying drawing forms a part, in which the separate parts of my improvement are designated by suitable reference characters in each of the views, and in which:—

Figure 1 is a side view of my improved tool showing the parts thereof folded together;—Fig. 2 a similar view showing the parts of the tool in position for use as a square and miter-square;—Fig. 3 a section on the line 3—3 of Fig. 2, and on an enlarged scale;—Fig. 4 a view similar to Figs. 1 and 2, but showing the parts of the device extended, as when used as a rule; and Fig. 5 a sectional view showing details of the construction of two parts of the rule.

In the practice of my invention, I provide a tool of the class specified which comprises four parts, *a*, *b*, *c* and *d*. The parts *a* and *d* are of the same length, or approximately so, and the parts *b* and *c* are approximately of the same length. Both ends of the part *b* are beveled at an angle of 45°, and one end of each of the parts *a* and *c* is correspondingly beveled, so that when the parts are folded or used in the position shown in Fig. 2, two inner and two outer angles each of 45° will be formed, and whereby scales of exact length and dimensions may be formed on the different parts of the tool and the use thereof facilitated.

The parts of the rule are provided, preferably on both sides, with a scale of inches and fractions thereof, and in the construction shown, my improved tool is designed to form, when desired, a rule of 24 inches or two feet long, as shown in Fig. 4.

The separate parts of the tool may be folded together as shown in Fig. 1, for con-

venience in carrying the same in a pocket or otherwise, and in Fig. 2, the said parts are folded so as to form a square and miter-square. In this use of the device, the part *c* extends, as shown at *c*², when the parts *a* and *d* are folded together, as shown in Fig. 3, to form the base *e* of the square. In this position of the parts, the extension *c*² of the part *c* does not interfere with the use of the device as a square, but rather facilitates the same as it forms a handle therefor, and the base *e* consists of the two parts *a* and *d*, as shown in Fig. 3, and between which is a space *e*².

One end of the part *b* is pivoted to one end of the part *c* at *f*, and the other end of the part *b* is pivoted to the part *a* at *g*, while the part *d* is also pivoted to the part *c* at *h*. The pivot pin *h*² by which the parts *d* and *c* are connected at *h* is fixed in the part *d* by means of a square head or rivet head *h*⁸ with which said pin is provided, and the part *c* is free to turn on said pivot pin, but is connected therewith by a beveled construction of said pin, and said pin is provided with a projecting head *h*³ having a nose *h*⁴.

It will be understood that the connection of the part *a* at *h* is a detachable connection, and said part *a* is provided with an oblong hole *h*⁵ through which the head *h*³ of the pin *h*² is adapted to pass, and said hole communicates with a circular recess *h*⁶ in the outer side of the part *a* to receive the projecting nose *h*⁴ of the head *h*³, and in which said nose is adapted to turn, and in connecting these parts at *h*³ the part *d* is swung parallel with the part *c*, after which the part *a* is turned into the position shown in Fig. 2, and the head *h*³ of the pin *h*² passes through the hole *h*⁵, after which the part *d* is swung into the position shown in Figs. 2 and 3, parallel with the part *a*, and the end *d*² of the part *d* is provided with an aperture *d*³ to receive the stud *g*² on the end of the pivot pin *g*³ by which the connection at *g* is made, said pivot pin being also provided with a head *g*⁴, and by means of this construction the parts of the tool are locked in the position shown in Figs. 1 and 2.

The part *b* is provided with a circular aperture *i* to receive the head *h*³ of the pivot pin *h*² when the parts are folded together, as shown in Fig. 1, and the part *a* is provided on its inner side with a recess *i*² which also receives the head *h*³ of the pivot pin

h^2 when the parts are folded together, as shown in Fig. 1, and by reason of the elasticity of the separate parts when thus folded, they will be locked together as will be readily understood. The part c is also provided with a circular recess i^2 which receives the stud g^2 of the pivot pin g^3 when the parts are folded together, as shown in Fig. 1, and the part d is provided with a recess i^4 to receive a corresponding knob i^5 on the part c , and the object of the parts i^2 and i^5 is to lock the part d in the extended position when the device is used as a rule, as shown in Fig. 4.

15 The operation of the device will be readily understood from the foregoing description when taken in connection with the accompanying drawing. Suppose the parts to be in the position shown in Fig. 1, 20 all that is necessary, when it is desired to use the device as a rule, is to extend the parts, as shown in Fig. 4. In this operation, the parts a and c are first swung in line with the part b after which the part d 25 is turned into the extended position, and it will be understood that the separate parts may be folded into the position shown in Fig. 2, from the position shown in Fig. 4, by first turning the parts b and c on the 30 pivotal connection at f into the position shown in said Fig. 2, and then turning the part a on the pivotal connection at g into the position shown in said figure and passing the head h^3 of the pivot pin h^2 through 35 the aperture h^6 , after which the part d is swung into the position shown in Figs. 2 and 3, and the free end thereof engaged with the stud g^2 of the pivot pin g^3 , and this operation turns the pivot pin h^2 so that 40 the head h^3 thereof will engage and lock the part a in position, this operation being effected by the nose h^4 of the head h^3 of the pin h^2 turning in the groove h^6 until it reaches the position shown in Fig. 2, in 45 which position all the parts are locked against movement, until the part d is again detached from its connection at g and swung back parallel with the part c .

My invention is not limited to the length 50 of the rule herein shown and described, nor to the exact length of the separate parts thereof, and the length of these parts may be varied so as to form a rule of any desired length, in which event the dimensions

of the square and miter-square will be correspondingly changed, and it will also be understood that the rule may be provided with different scales of any kind or class. It will also be seen from the foregoing description that the square shown in Fig. 2 55 comprises a base, a perpendicular and a hypotenuse, and the perpendicular is provided with a part which extends beyond the base and which forms a handle for the manipulation of the device, the base being 60 also composed of two separate parallel parts whereby the other side of the device 65 can be conveniently used as a square or miter-square.

Having fully described my invention 70 what I claim as new and desire to secure by Letters Patent is:—

1. A combination tool of the class described composed of four parts, one of said parts being beveled at an angle of 45° at 75 both ends and two of said parts being beveled at a corresponding angle at one end only, said parts being connected substantially as shown and described.

2. A tool of the class described composed 80 of four parts one of which is beveled at an angle of 45° at both ends and two of which are beveled at an angle of 45° at one end, the beveled ends of the last named parts being respectively pivotally connected 85 with the opposite ends of the part both ends of which are beveled, the fourth part being pivotally connected with one of the parts one end only of which is beveled and at a predetermined distance from the unbeveled 90 end thereof, and the free end of the other part which is beveled at one end only being adapted to be detachably connected with said last named parts at the same point, and said fourth part being adapted to be 95 swung parallel with the last named part and to be connected therewith at that end thereof which is connected with one end of the part both ends of which are beveled.

In testimony that I claim the foregoing 100 as my invention I have signed my name in presence of the subscribing witnesses this 24th day of February 1913.

ALBERT J. TOBIE.
